UNITED STATES PATENT OFFICE.

FREDERICK J. HUMPHREY, OF KALAMAZOO, MICHIGAN, ASSIGNOR TO GENERAL GAS LIGHT COMPANY, OF KALAMAZOO, MICHIGAN.

GLOBE-HOLDER.

1,139,684.

Specification of Letters Patent. Patented May 18, 1915.

Application filed June 24, 1914. Serial No. 847,108.

To all whom it may concern:

Be it known that I, FREDERICK J. HUMPHREY, a citizen of the United States, residing at Kalamazoo, Michigan, have invented certain new and useful Improvements in Globe-Holders, of which the following is a specification.

This invention relates to improvements in globe holders.

10 In using the term globe holder in this application I intend that it shall be considered to embrace shades, reflectors and the like where they are supported in substantially the same manner as by my holder, which 15 is adapted for holding shades, reflectors and the like, and is adapted for both gas and electric fixtures.

The main objects of this invention are to provide an improved globe holder in which 20 the parts are simple and economical in structure and easily assembled and when assembled cannot become accidentally disassembled, and at the same time to provide a structure which effectively supports the 25 globe in a central position and one which is easy and simple to operate.

Further objects, and objects relating to structural details, will definitely appear from the detailed description to follow.

30 I accomplish the objects of my invention by the devices and means described in the following specification.

The invention is clearly defined and pointed out in the claims.

35 A structure which is a preferred embodiment of my invention is clearly illustrated in the accompanying drawing forming a part of this specification, in which:

Figure I is a detail side elevation of a 40 lamp structure embodying the features of my invention. Fig. II is a horizontal section on a line corresponding to the broken line 2—2 of Fig. I. Fig. III is an enlarged detail vertical section on a line corresponding to line 3—3 of Fig. II. Fig. IV is a detail inside view showing structural details. Fig. V is a perspective view of one of the retaining members.

In the drawing similar reference characters refer to similar parts throughout the 50 several views, and the sectional views are taken looking in the direction of the little arrows at the ends of the section lines.

Referring to the drawing, the body or casing 55 1 of the lamp, which may be of any suit-

able design, is provided with a cylindrical globe holder collar or gallery 2 at its lower end having an inturned flange 3 at its lower edge. The globe 4 is inserted into the bottom of the gallery and is provided with a flange, not shown, with which the ring 5 engages, as is well understood in the art. The supporting ring 5 is formed of wire and has a rear loop 6 and side loops 7 formed therein and projecting laterally to constitute supporting fingers. The collar or gallery 2 has a rear slot 8 and a pair of side slots 9 with which the supporting fingers are engaged as is shown in detail in Figs. II and III. The front ends 10 of the support 70 5 are crossed and are disposed tangentially through the spaced front slots 11, the ends 10 being crossed between the slots, as shown in Fig. II. The side slots 9 are of such length as to permit lateral and longitudinal 75 movement of the side loops or fingers therein. The rear slot is of such length that the rear loop or finger 6 is a sliding fit therein. The front slots 11 are of such length that the contractive action of the ring holds the 80 ends against the outer ends of the slot and this normally holds the side fingers 7 against the front ends of the slots 9. This effectively centers the ring.

To expand the ring for removal or insertion of the globe the two ends of the ring are grasped, as between the thumb and finger and pressed together, which throws the side fingers outwardly and rearwardly in the slots and forces the finger 6 rearwardly in 90 the rear slot 8. When the band is released the contraction of the spring not only causes it to engage the globe but also centers the ring as described. The ends of the ring are formed of loops 12 to provide finger 95 pieces. The slots 11 are preferably arranged with their centers in slightly different planes, as illustrated, so that the ends 10 are properly supported in their crossed relation. The fingers or loops 6 and 7 are all in the 100 same plane and are straight. This permits the parts being quickly and easily assembled.

To prevent the accidental displacement of the side loops from the slots I provide retaining members 13. These retaining members are, in the structure illustrated, formed of strips of metal folded to provide cross heads at one end and arranged through the slots between the arms of the loops and the ends 14 folded oppositely against the collar 110

or gallery whereby the retaining members are slidably retained in the slots, that is, they are retained so as to permit lateral movement when the fingers are moved laterally in the slots. The fasteners are prevented from swinging into alinement with the slots and thus becoming disengaged by the arms or sides of the loops. The retainers thus formed are inconspicuous and at the same time allow full freedom of movement of the side loops 7 in the slots, both laterally and longitudinally.

My improved globe holder is very simple and economical in structure and the parts are simple and economical to assemble and it is very easily operated and very effectively supports the globe.

Having thus described my invention what I claim as new and desire to secure by Letters Patent, is:

1. The combination with the collar of a light fixture having a rear slot, a pair of opposed side slots and front slots, of a contractive ring formed of wire disposed within the collar and having side and rear supporting loops engaged in the side and rear slots, the ends of the ring being crossed and disposed tangentially through the front slots, the length of the side slots being greater than the width of the side loops permitting lateral and longitudinal movement of the side loops in the side slots as the ring contracts and expands, the ends of the ring being held normally in engagement with the outer ends of the front slots and the side loops against the front ends of the side slots by the contraction of the ring, and retaining members carried by the collar disposed through the loops and engaging the side slots for sliding movement therein.

2. The combination with the collar of a light fixture having a rear slot and a pair of opposed side slots, of a ring formed of wire disposed within the collar and having side and rear supporting loops engaged in the side and rear slots, the length of the side slots being greater than the width of the side loops permitting lateral and longitudinal movement of the side loops in the side slots as the ring contracts and expands, and retaining members carried by the collar disposed through the loops and engaging the side slots for sliding movement therein.

3. The combination with the collar of a light fixture having a slot therein, of a supporting ring formed of wire having a loop disposed in the slot for lateral and longitudinal movement in the slot, and a retaining member formed of a strip of metal

folded upon itself to provide a cross head 60 at one end arranged through the slot between the arms of the loop, the ends of the retaining member being folded in opposite directions against the side of the collar whereby it is retained in the slot for sliding 65 movement therein, the rotative movement of the retaining member in the slot being limited by the loop.

4. The combination with the collar of a light fixture having a slot therein, of a supporting ring formed of wire having a loop 70 disposed in the slot, and a retaining member formed of a strip of metal folded upon itself to provide a cross head at one end arranged through the slot with its cross-head between the arms of the loop, the ends of the retaining member being folded 75 against the side of the collar whereby it is slidably retained in the slot and so as to permit its lateral movement with the lateral 80 movement of the loop.

5. The combination with the collar of a light fixture having a slot therein, of a supporting ring formed of wire having a loop 85 disposed in the slot, and a retaining member provided with a cross head at one end arranged through the slot with its cross head between the arms of the loop the end of the retaining member being turned laterally on the other side of the collar whereby 90 it is slidably retained in the slot and so as to permit its lateral movement with the lateral movement of the loop.

6. The combination with the collar of a light fixture having a slot therein, of a ring 95 formed of wire disposed within the collar and having a loop constituting a supporting finger engaged in the slot for lateral and longitudinal movement therein, and a retaining member carried by the collar disposed within the loop and engaging the slot for sliding movement therein.

7. The combination with the collar of a light fixture having a slot therein, of a ring 105 formed of wire disposed within the collar and having a loop engaged in the slot for lateral and longitudinal movement therein, and a retaining member disposed through the loop and movable on the collar to permit lateral movement of the loop.

In witness whereof, I have hereunto set my hand and seal in the presence of two witnesses.

FREDERICK J. HUMPHREY. [L. s.]
